ROTARY AIR BRUSH.

No. 506,450.

Patented Oct. 10, 1893.

Diagram illustrating a curved metal strip, labeled *fig. 11.* The strip is shown with a central rib and two ends labeled *K* and *K'*. The ends *K* and *K'* are marked with small circles, and the central rib is marked with a small circle labeled *X*. The strip is shown in two positions, with the right side being a mirror image of the left.

UNITED STATES PATENT OFFICE.

JUDSON S. WERTSBAUGHER AND GEORGE H. McCUNE, OF FORT WAYNE,
INDIANA.

ROTARY AIR-BRUSH.

SPECIFICATION forming part of Letters Patent No. 506,450, dated October 10, 1893.

Application filed August 2, 1893. Serial No. 482,151. (No model.)

To all whom it may concern:

Be it known that we, JUDSON S. WERTS-
BAUGHER and GEORGE H. McCUNE, citizens of
the United States, residing at Fort Wayne, in
5 the county of Allen and State of Indiana,
have invented a new and useful Improvement
in Rotary Air-Brushes, which are used
in making pictures of persons, such as en-
larging photos, &c., of which the following is

10 a specification.

The objects of our invention are to con-
struct a cheap, simple and durable air brush,
and one that is not likely to get out of order.
We attain these objects by the mechanism
15 illustrated in the accompanying drawings, in
which—

Figure 1, is a perspective view of a com-
plete brush. Fig. 2, is an edge view of a
brush showing handle removed and the shank
20 in section. Fig. 3, is a detail view of ink
wheel. Fig. 4, is a section of the shank, and
detail of the air tubes. Fig. 5, is a perspec-
tive view of a complete brush showing an op-
posite side from Fig. 1. Figs. 6, 7 and 8 are
25 detail views of the ink wheel. Fig. 9, is a
view of the ink tube holder. Fig. 10, is a section
of a part of the shank showing the air
passages, and Fig. 11, is a view of the air
valve.

30 Similar letters refer to similar parts through-
out the several views.

The shank A is made bifurcated at one
end having prongs B and C, between which
the ink wheel is journaled; as shown in Figs.
35 1, 2, and 5. The other end of the shank is
rounded and made hollow so as to receive the
handle D. The handle contains a small tube
40 E which projects through the outer end of the
handle and extends up against the inside of
the shank, registering over two small holes
or air passages F F' which lead to the air valve
45 G, most clearly shown in Fig. 4. The said
air valve is made round and passing through
the shank it is held in its position by a washer
H and screw I. The valve is made movable
50 in its position by the handle or lever J which
extends outward toward the handle D and par-
allel therewith. The outer end of the said le-

ver J is checked and made suitable to be con-
trolled by the thumb while the brush is held in
50 the hand in use. On the body of the valve G
there are two grooves K K', which are cut taper-
ing, or wider at one end than at the other, the
said grooves commencing very small at a point
55 marked X and widening as they extend around
the said body, but the said grooves do not
extend entirely around the said body, as the
smooth strip marked X' intervenes to prevent
the ends of the grooves from meeting and also
closes the inner passages F F' when the lever
60 is resting in the closed position shown in Fig.
4, in which position the direction of said lever
is parallel with the shank and handle. When
the lever is turned outward as indicated by
the arrow in Fig. 1, the grooves come around
65 to the openings F F'. The outlet of the air is
increased as the lever is turned outward,
caused by the widening of the grooves K K'.
The air passage F is delivering air to the ink
spray, and the outlet F' delivers air to the
70 tube L which causes the air wheel to revolve.
The tube L projects from between the prongs
B and C, at an angle so as to strike the pock-
ets M as indicated by the dotted arrow in Fig.
75 3, causing the wheel to revolve as indicated
by the solid arrow in said figure. The air
passing through the outlet F and groove K
goes out through a small tube N which is se-
cured in the shank on the top side of the said
80 shank as shown in Figs. 1 and 2. The air passes
from the tube N into the tube O as shown in
Figs. 1 and 2. The tube O is held firmly in
its position by a connection Q, the said con-
nection Q is held to a stud R by set screw S,
85 and a similar set screw S' holds the tube O
firmly in the said connection Q, all as shown
in Figs. 1 and 2. The stud R and pipe N are
cast or otherwise secured to the upper side
of the shank A, and the outlet end of the
90 tube O is pointed so as to reduce the exhaust
air to a very small jet.

What we shall term the inkwheel com-
prises the power-wheel T, having parallel cir-
cular sides secured upon the hub T', and buck-
ets M disposed peripherally between the said
95 circular sides; a circular sectional wire rim

- U concentric with the power-wheel and a disk or washer V to which the sectional rim is soldered or otherwise secured and which is itself secured by screws V' to one side of the power wheel. The ink wheel is journaled, between the prongs B and C, by a screw shaft W, and the ink wire U is made to run close to the air jet from the tube O, and to draw or rub the sponge Y, most clearly shown in Fig. 1.
- 10 The ink tube Z is made hollow and in two parts, the end Z fitting into the holder Z'' so that the slot Z''' will register in line with the ink wheel, all as shown in Figs. 1 and 5. The cap Z' is removable for convenience in filling.
- 15 The tube holder Z'' is secured to the shank by a set screw Z'''' passing through the slot Z'''''. A small soft sponge Y is inserted in the lower end of the ink tube so as to fill up the slot Z''' and to prevent the ink from running out 20 too freely.

The operation of our invention is as follows: The ink tube is charged or loaded with ink, by removing the cap Z'; after filling, the cap Z' is replaced thus closing the ink-tube.

25 The air is applied to the brush from some suitable blower or pump by attaching a hose to the end of the tube E, the brush is held in the right hand with the prong B on the under side and held next to the paper, the air jet 30 from the tube O pointing directly at the paper. By turning the valve lever J outward the air at once begins to flow through the tube O striking the wire rim U, and air at the same time flows out at the tube L against the buckets of the wheel T causing it to revolve rapidly 35 in the direction indicated by the arrow in Fig. 1. By the wheel revolving the wire rim U is drawn through the sponge in the slot in the lower end of the ink tube, thereby gathering a small deposit of ink on the wire and when said wire comes around under the strong blast of air from the pipe O the ink is blown off in a fine mist against the paper; the amount of the mist varying according to 40 the amount of air turned on by the valve J.

45 Having thus described our invention, what we claim, and desire to secure by Letters Patent, is—

1. In a device of the class described, the 50 combination of the power wheel journaled to rotate in bearings, an ink or paint supply, a rim carried by the power wheel and adapted to receive ink from the ink-supply, and an air-tube adapted to discharge against the rim, substantially as described.

55 2. In a device of the class described, the combination of the handle, the power wheel journaled to rotate in bearings on the handle, an ink-supply, a rim carried by the power 60 wheel and adapted to receive ink from the ink supply, an air tube adapted to discharge a current of air to drive the power wheel, and a second air tube adapted to discharge a current of air against the rim, substantially as described.

65 3. In a device of the class described, the

combination of the handle, a power wheel journaled in bearings on the handle, an ink-supply, a rim carried by the power wheel and adapted to receive ink from the ink supply, 70 a main air tube adapted to discharge a jet of air against the power wheel to drive the same, a branch air tube leading from the main air tube and adapted to discharge a jet of air against the rim, and a valve and an operating 75 lever therefor located at the junction of the main and branch air tube to regulate the flow of air through both, substantially as described.

4. In a device of the class described, the 80 combination of the power wheel journaled to rotate in bearings, an ink supply secured to the handle, a rim carried by the power wheel and adapted to receive ink from the ink supply, an air tube adapted to deliver a jet of 85 air against the power wheel to drive the same, and a second air tube adapted to deliver a jet of air against the rim, substantially as described.

5. In a device of the class described, the 90 combination of the handle, a power wheel journaled in bearings in the handle, a rim carried by the power wheel, an ink supply tube secured to the handle and having a slot or opening on the side adjacent the rim, a 95 sponge in the opening adapted to receive ink from the ink supply tube and to transfer the same to the rim when the latter is rotated, an air tube adapted to discharge a jet of air against the power wheel to drive the same 100 and a second air tube adapted to discharge a jet of air against the rim, substantially as described.

6. In a device of the class described, the combination of the power wheel, a wire rim 105 carried by the power wheel, means for furnishing a constant supply of ink to the wire rim, and an air tube adapted to discharge a jet of air against the rim to drive the ink therefrom, substantially as described. 110

7. In a device of the class described, the combination of the power wheel provided with buckets to adapt it to be driven by a jet of air, an extension rim U carried by the power wheel, an ink supply tube, an air passage adapted to deliver a jet of air at an angle against the buckets of the power wheel, a second air passage adapted to deliver a jet against the rim, a valve G provided on its body portion with two grooves K K' which 115 register respectively with the aforesaid air passages, and means for controlling the said valve whereby the jets of air through both air passages may be controlled by a single valve, substantially as described. 120

8. In a device of the class described, the combination of the handle, the power wheel journaled in bearings at one end of the handle, a rim U carried by the power wheel, an ink-tube carried by the handle and adapted 125 to deliver ink to the rim, an air supply tube E leading to the handle, an air passage F' 130

leading from the air supply tube, and adapted to deliver a jet of air against the power wheel to drive the same, a second air passage F adapted to deliver a jet of air against the said rim U, and a single valve G adapted to control the flow of air through both passages, substantially as described.

In testimony whereof we affix our signatures in presence of two witnesses.
